UNITED STATES PATENT OFFICE.

GEORGE W. SPIKES, OF DALWORTH PARK, TEXAS.

DESIGN FOR A HONEY RECEPTACLE.

Application filed June 10, 1922. Serial No. 2,606. Term of patent 7 years.

To all whom it may concern:

Be it known that I, GEORGE W. SPIKES, a citizen of the United States, residing at Dalworth Park, in the county of Dallas and State of Texas, have invented a new, original, and ornamental Design for Honey Receptacle, of which the following is a specification, reference being had to the accompanying drawing, forming part thereof.

The figure is a perspective view of a honey receptacle, showing my new design.

I claim:

The ornamental design for a honey receptacle as shown.

GEO. W. SPIKES.
